UNITED STATES PATENT OFFICE.

CHESTER GREEN, OF CORNWALL LANDING, NEW YORK.

SAFETY-CRANK.

1,383,101.

Specification of Letters Patent. Patented June 28, 1921.

Application filed August 25, 1920. Serial No. 406,003.

To all whom it may concern:

Be it known that I, CHESTER GREEN, a citizen of the United States, and resident of Cornwall Landing, in the county of 5 Orange and State of New York, have invented a new and Improved Safety-Crank, of which the following is a full, clear, and exact description.

It is well appreciated that numerous accidents have occurred in connection with cranking internal combustion engines, due to a premature ignition in one of the cylinders which has resulted in what is commonly known as a "back fire" and consequential back-lash, on the part of the starting crank.

With this in view, numerous cranks have been provided which have sought to overcome this defect. Most of these cranks have 20 in mind the provision of a certain construction which would automatically serve to withdraw the pawl, or engaging end of the crank, out of engagement with the end of the crank shaft upon a "back fire" occurring.

Almost without exception, however, these devices have proven impractical for the reason that a certain amount of back-lash on the part of the crank handle necessarily 30 existed before the parts moved out of engagement. This back lash usually through an arc of approximately 90° was sufficient to cause a serious injury to the operator, especially if he were exerting any unusual 35 amount of force in an effort to turn the motor over.

Further, it has often occurred, that safety cranks of this type have entirely failed to operate so that no benefits have been derived 40 from their use, in an emergency when a backlash occurred.

Having these defects in mind, I have now constructed a safety crank which is particularly adapted for use in turning an internal 45 combustion engine over for starting the same, but which is not necessarily limited to this adaptation, and by means of which, upon a back fire occurring, a retrograde movement will result through an arc of such 50 smallness as to be well nigh imperceptible, so that no danger of injury to the operator may result.

A further object of my invention is the construction of a safety crank which shall 55 operate under all conditions in the event

of a back fire so that the same may be implicitly relied upon to function.

Reference is had to the attached sheet of drawings as illustrating practical embodiments of my invention, and in which drawings:

Figure 1 is a front view of a safety crank constructed in accordance with my invention.

Fig. 2 is an enlarged sectional side view 65 taken along the line 2-2 of Fig. 1, and

Figs. 3 and 4 are fragmentary sectional views taken along the lines 3-3 and 4-4 respectively of Fig. 2 in the direction of the arrows.

In these views the reference numeral 5 indicates a pair of spaced annular plates, between which is interposed a ring 6 presenting a ratchet 7 in its inner face, such ring being retained in applied position by 75 any suitable means such as screws 8.

A pair of ears 9, are rigidly secured to these portions, and serve to retain the whole in applied position upon the front of a motor vehicle or other position to which they 80 may be attached, by virtue of bolts or other suitable retaining means 10, which engage a fixed portion of the vehicle or other element.

A crank handle 11 is pivotally suspended 85 as at 12 from a bracket 13, which bracket forms an integral portion of a hollowed disk 14. The disk 14 presents a projecting portion in the nature of a sleeve 15, such disk further providing an inwardly extending annular flange 16 adjacent the base of said sleeve 15 for a purpose hereinafter more 90 fully specified.

A male disk 17 is adapted to extend into the hollowed disk, such former disk presenting a tubular extension 18 terminating at a point beyond either edge of the sleeve 15. An expansion spring 19 is conveniently interposed between the flange 16 and a washer 20 retained in applied position by 100 means of a nut 21, which is secured to the tubular extension 18.

It will be understood that the hollowed disk 14 and the male disk 17 will be moved toward one another, and will serve to frictionally engage and cause interengagement 105 between a plurality of clutch gears 22. The disks 22 may be of any suitable number, and it is to be noted that alternate disks are keyed to the male disks 17 as at 23, and to 110

the hollowed disk 14 as at 24 respectively. By virtue of this construction it will be readily understood that the rotational force exerted by the crank 11 will be imparted to the hollowed disk 14 which in turn will exert rotational force upon the clutch disks 22, this latter action transmitting its force to the male disk 17.

A crank shaft engaging member 25, of any desirable construction is positioned adjacent the outer end of the disk 17, and is retained in this position by virtue of a squared shaft 26 longitudinally movable within the disk 17, which shaft is continued as at 27, and terminates at a point beyond the outer end of the tubular extension 18 in a plane at which the inner end of the crank 11 may engage the same.

A spring 28 is interposed between a portion 20 of the extension 18 and an adjustable stop 29 secured adjacent the outer end of the shaft 27 so that the engaging member 25 will be normally retained in its retracted position (indicated in full lines) it being noted however 25 that upon the crank 11 being swung to the position indicated in dotted lines in Fig. 2, that the shaft 26 will be projected, causing a projection on the part of the engaging member 25 to the position also indicated in dotted lines, at which position it may engage the end of the crank shaft or other object to be turned.

Finally it will be noted that the outer face of the hollowed disk 14 is conveniently formed with an outwardly extending portion 30 approximately intermediate its side edges, which portion terminates at a point adjacent the inner ends of the ratchet 7.

A plurality of pawls 31 divided into two 40 annular series, are positioned adjacent the forward and rear edges of the hollowed disk 14, and to each side of the outwardly extending portion 30. In this connection it is to be noted that the pawls 31 have springs 45 32 associated with them which serve to press the same outwardly, as has been indicated in Figs. 3 and 4. Further, it will be seen that the individual pawls 31 are so arranged that certain of the same are at all times adjacent 50 or substantially adjacent one of the teeth of the ratchet 7 for a purpose hereinafter brought out.

It will now be noted in operation, assuming that the ears 9 have been attached in the 55 manner aforeslated, to properly position the parts that the crank handle 11 may primarily be rocked around its pivot 12, which will result in a projection on the part of the shaft 26—27, and consequently a projection 60 of the engaging member 25 secured thereto. This member will now have been moved to the position indicated in dotted lines, at which point it will engage the shaft to be rotated.

65 It will be obvious, due to the frictional

engagement existing between the disks 14 and 17, and the interposed plurality of disks 22, and the connection of this latter, that upon a rotational force being imparted to the crank 11 that this force will be in turn transmitted to the engaging member 25 in a manner which has been aforescribed.

Now assuming that a back fire occurs, or in other words, that an anti-clockwise motion is imparted to the engaging member 25, 75 it will be seen that this rotational force will be imparted to the male disk 17, and by virtue of the fact that the centermost plate 22 is keyed to this disk, as at 23, this force will be imparted to the plate specified, and in turn, by virtue of the frictional inter-engagement of the plates or disks 22, and the connection of certain of the same, as at 24 to the hollowed disk 14, this latter member will be turned.

However, upon this motion being imparted, it will be seen that by virtue of the fact that the pawls 31 are not spaced in such a manner as to align or be equidistant from the teeth of the ratchet 7, that the most imperceptible retrograde motion will permit one of these pawls to engage its corresponding ratchet which will materially result in cessation of turning on the part of the hollowed disk 14, by virtue of the fact 95 that this member as aforescribed, is secured by the ears 9 to a fixed portion of the element with which it is associated.

The disk 14 now being incapable of turning farther will prevent any motion on the 100 part of the plates 22 which are associated as at 24. The male disks 17 however will continue to move in the direction imparted to it by the back fire, and it will be seen that this will result in the clutch, formed by 105 the interposed plates and faces of the hollowed disk and male disk, slipping.

Obviously immediately upon a back fire occurring the handle 11 may be swung downwardly, thus relieving the strain upon the 110 parts by moving the engaging member back to its normal position.

Obviously numerous modifications of structure might readily be resorted to without in the least departing from the spirit 115 of my invention, which I claim as:—

1. A safety crank including a clutch comprising a hollowed plate, a male plate, a plurality of plates interposed between said first named plates, certain of said latter plates being secured to said hollowed plate, the further plates of said clutch being secured to said male plate, a sleeve forming a part of said hollowed plate, an outwardly extending flange adjacent the base of said sleeve, 120 an extending portion forming a part of said male plate and projecting through said sleeve and beyond the same, a spring interposed between said flange and projecting portion of the male plate, an engaging mem- 130

ber secured to said male plates, and means for rotating said hollowed plates.

2. A safety crank including a clutch comprising a hollowed plate, a male plate, a plurality of plates interposed between said first named plates, certain of said latter plates being secured to said hollowed plate, the further plates of said clutch being secured to said male plate, a sleeve forming a part of said hollowed plate, a forwardly extending flange adjacent the base of said sleeve, an extending portion forming a part of said male plate and projecting through said sleeve and beyond the same, a spring interposed between said flange and projecting portion of the male plate, a shaft extending through said male plate and beyond the ends of the same, an engaging member secured to one of the ends of said shaft, a crank handle secured to said hollowed plate, the end of said pivotally mounted crank being adapted to engage the end of said shaft for projecting the same.

3. A safety crank including a clutch comprising a hollowed plate, a male plate, a

plurality of plates interposed between said first named plates, certain of said latter plates being secured to said hollowed plate, the further plates of said clutch being secured to said male plate, a sleeve forming a part of said hollowed plate, a forwardly extending flange adjacent the base of said sleeve, an extending portion forming a part of said male plate and projecting through said sleeve and beyond the same, a spring interposed between said flange and projecting portion of the male plate, a shaft extending through said male plate and beyond the ends of the same, an engaging member secured to one of the ends of said shaft, a crank handle secured to said hollowed plate, the end of said pivotally mounted crank being adapted to engage the end of said shaft for projecting the same, and a spring interposed between the end of said shaft and said male plate for normally retaining said shaft and engaging member in retracted position.

CHESTER GREEN.
